Primary Examiner — Marcus A Jackson(57) **CLAIM**

The ornamental design for set of halogen headlights, as shown and described.

DESCRIPTION

FIG. 1 is a top, front, left perspective view of set of halogen headlights embodying our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line representations in the figures show unclaimed environment or boundaries, and thus form no part of the claimed design. The brackets shown in the drawings indicate a set of halogen headlights and form no part of the claimed design.
